UNITED STATES PATENT OFFICE.

MAE R. WILLIAMS, OF ST. LOUIS, MISSOURI.

TOY.

1,420,597.

Specification of Letters Patent. Patented June 20, 1922.

Application filed March 9, 1920. Serial No. 364,453.

To all whom it may concern:

Be it known that I, MAE R. WILLIAMS, a citizen of the United States, residing at St. Louis, in the State of Missouri, have invented new and useful Improvements in Toys, of which the following is a specification.

This invention relates to toys, and comprehends the provision of a foot operated wheeled toy designed to represent a tank, the latter being equipped with a gun, and means for producing a clicking sound to represent the sounding of the gun, also providing a signal for the toy.

The nature and advantages of the invention will be better understood when the following detail description is taken in connection with the accompanying drawings, the invention residing in the combination and arrangement of parts as claimed.

In the drawings forming part of this specification like numerals of reference indicate similar parts in the several views and wherein:

Figure 1 is a side elevation of the toy constructed in accordance with my invention.

Figure 2 is a vertical longitudinal sectional view.

Figure 3 is a top plan view.

Figure 4 is a transverse sectional view.

Figure 5 is an enlarged detail view taken on the line 5—5 of Figure 1.

Referring to the drawings in detail, A indicates generally the body of the toy, which is designed to represent a tank of the well known construction used during the recent war. The sides of the tank are indicated at 10 and are flanged as at 11, the sides being connected by the end members 12. The bed is indicated at 13 and supports a seat 14 for the user. The space between the seat proper and the bed 13 defines a compartment wherein articles of suitable size may be conveniently carried in the toy access to this compartment being controlled by means of a door 16. The end members terminate in spaced relation at the top of the tank and provides for an entrance to the toy. The toy is supported on wheels, the front wheels being indicated at 17, and mounted on suit-

able axles 18, while the driving wheels 20 are associated with the axle 21. The latter mentioned axle is provided with oppositely disposed crank portions 22 each of which has associated therewith one end of a pitman 23, the forward corresponding extremities of these pitmen being movably associated or connected with the bed 13. The pitmen support pedals 25 by means of which the pitmen are actuated by the feet of the user in order to rotate the rear axle 20 that propels the toy over the ground or surface.

Carried by one of the end members adjacent the top thereof is a member indicative of a gun, the member being shown at 26. 65 Carried by the rear end of the this gun, is a leaf spring 27. A shaft 28 is journaled for rotation in the manner shown and is operated by means of a handle 29. Radiating from the shaft 28 is a plurality of blades 30 70 which are successively brought into contact with the spring 27 to produce a clicking noise, indicative of the firing of the gun. In addition to being used for this purpose, this mechanism is used as a signal for the 75 toy. The component parts of the toy, may be constructed from wood, metal or any other suitable material, and the toy in its entirety varying in size without departing from the spirit of the invention.

While I have shown and described what I consider the preferred embodiment of the invention, I desire to have it understood that I do not limit myself in this connection, and that such changes may be resorted to 85 when desired as fall within the scope of what is claimed.

Having thus described my invention what I claim as new is—

A wheeled toy comprising a body portion 90 designed to represent a tank and including spaced side members of similar outline, inwardly directed flanges projecting from the respective side members, curved end members connecting the side members and spaced 95 inwardly from said flanges, a bed or box-like formation arranged between the said side members and wholly disposed within the confines thereof, one wall of said bed being extended entirely across the body portion of 100

the toy and engaging the said flanges, the adjacent end of one of the curved end members being connected with said wall, a gun projected through said wall and reposing upon said adjacent curved member, a seat supported by said bed and connected with the other of said curved end members, said

seat and bed defining a compartment by the intervening space therebetween, a hinged door forming part of one of said side members, means for propelling said toy and means for steering the latter.

In testimony whereof I affix my signature.

MAE R. WILLIAMS.
